MUFFLER

Robert W. Compo, Defiance, Ohio

Application July 24, 1936, Serial No. 92,306

2 Claims. (Cl. 181—47)

My invention relates to mufflers for eliminating the explosive sound of the exhaust of internal combustion engines.

The high intermittent pressure of the exhaust gases in the use of my invention is progressively dissipated by counterpneumatic shock-absorbing pressures automatically created by the pressures of the exhaust.

The invention consists in providing a muffler for internal combustion engines having one or more cones disposed in series or tandem arrangement, interconnected only through the apices of the cones and communicating with surrounding closed chambers through restricted openings in the walls of the cones to produce automatically rising pressures of the trapped air in each of the chambers which is counter to the pressures of the exhaust gases and thereby progressively absorbing the explosive pressure of the pulsating exhaust gases and cause the delivery of the gases at a substantially constant stream flow.

The invention may be contained in mufflers that vary in their details and to illustrate a practical application of the invention, I have selected a muffler containing the invention as an example of the various structures in which the invention may be embodied. The particular muffler referred to is shown in the accompanying drawing and is described hereinafter.

Fig. 1 is a longitudinal section of the muffler particularly referred to. Fig. 2 is an enlarged section of one end part of the muffler wherein the details of the structure are more clearly illustrated than in Fig. 1. Fig. 3 is a view of a section taken on the plane of the line 3—3 indicated in Fig. 2.

In the muffler 1 shown in the drawing, a plurality of axially aligned cones 2, 3, and 4 are located in a shell 6 and connected in tandem whereby the smaller end of each cone is connected to or communicates with the larger end of the succeeding cone. The shell 6 is provided with the ends or heads 7 and 8. The head 7 has an inlet port 9 to which the exhaust pipe of the engine may be connected, and the head 8 has an outlet port 11 to which the tail pipe is connected for delivery of the exhaust products from the muffler.

The shell is divided into the chambers 12, 13, 50 14, and 15 by the circular plates 16 and 17 and 18 having flanged parts that fit the interior surfaces of the shell and flanged parts that fit the open apices of the cones. The plates are formed solid, that is, without openings, and, except for 55 the connection through the apices of the cones,

form closed chamber parts exterior to the walls of the cones. The cones are located in the chambers 12, 13, and 14, respectively, and the gases are delivered from the last cone of the series into the chamber 15 whence the gases are discharged through the port 11 and the tail pipe. The larger ends of the cones fit the inner surfaces of the shells, and the apices fit the flanged openings 19 formed in the central parts of the plates 16, 17, and 18. The cones are without heads and therefore the exhaust gases as they enter the chambers in which the cones are located, freely expand and by their pressure are forced into the cones in succession.

The sides of the cones are provided with a plurality of small openings. Preferably slotted openings 22 are formed in the walls of the cones and are located in the planes of the axes of the cones. In the forming of the slotted openings 22, edge parts of the slots are pressed outward to 20 form louvers. The edges of the slots are in the planes of the axes of the cones, and so as to direct the gases from the cones into the chamber parts exterior to the cones in directions extending tangential to the surface of the cones. The openings of the louvers may be arranged in rows and the openings of the alternate rows may be such as to direct the gas streams in directions that are counter to each other with respect to the circle of the cones in which the openings may be located to produce counterpressure by the influx of exhaust gases into the chamber parts exterior to the cones and thus prevent rotative whirling movement of the gases as they enter the chamber parts and as they are returned to the interior of the cones.

Upon entrance of the exhaust gases into each cone, through the restricted inlets, expansion within the larger end of the cone immediately occurs. Also the exhaust gases are forced through the wall openings of each cone counter to the pressure of the air within the chamber part exterior to the cone which is trapped therein, and the peak of the pulsating pressure is progressively leveled as the pulsation moves toward the delivery end of the muffler.

The trapped air in the chamber parts exterior to the cones thus yieldingly counteracts the pulsating exhaust pressure and operates to return exhaust gases to within the cone as the pressure of the exhaust gases reduces and while the cone is exhausting into the succeeding cone and chamber where the gas again expands but with a greatly reduced pressure. The velocity flow is greatly decreased as the pulsations of the exhaust gases

progress through the muffler until the exhaust gases enter the chamber 15 whence they are discharged at a substantially constant rate of stream flow.

5 I claim:

1. In a muffler, a shell, the ends of the shell having inlet and outlet ports and a plurality of partitioning plates forming chambers, cones located in axial alignment and in certain of the 10 chambers, the larger ends of the cones fitting the side wall of the shell and the smaller ends of the cones opening into the larger ends of the next succeeding cones, the inlet port opening into the interior of the end of the first cone, the side 15 walls of the cones having slotted openings arranged in rows and located in the planes of the axes of the cones, edge parts of the slotted openings pressed outwardly to form louvered openings to direct gas from alternate rows of openings into the chamber parts exterior to the cones in substantially opposite directions and raising the 20 pressure of the trapped air in the chamber parts by the pressure of the exhaust gases for progressively reducing the intermitting pulsating pres-

sure and producing a substantially constant stream flow through the outlet.

2. In a muffler, a shell, the ends of the shell having inlet and outlet ports, a cone located in the shell, the larger end of the cone fitting the 5 side wall of the shell, the inlet port opening into the interior of the larger end part of the cone, the smaller end of the cone communicating with the outlet port, the side wall of the cone having slotted openings arranged in rows and located in 10 the planes of the axis of the cone, the edge parts of the slotted openings pressed outwardly to form louvered openings to direct gas from alternate rows of openings into the chamber part intermediate the exterior of the cone and the interior 15 wall of the shell in substantially opposite directions and raising the pressure of the trapped air in the said chamber part by the pressure of the exhaust gas which returns the exhaust gas to the cone from the said chamber part upon reduction 20 of the pressure of the exhaust gas and thereby produces a substantially constant stream flow through the outlet.

ROBERT W. COMPO.
